UNITED STATES PATENT OFFICE.

EMERY M. McVICKER, OF MILWAUKEE, WISCONSIN, ASSIGNOR TO J. F. McVICKER, OF MILWAUKEE, WISCONSIN.

RAIL-ANCHOR TIE PLATE.

Application filed March 9, 1925. Serial No. 14,061.

To all whom it may concern:

Be it known that I, EMERY M. McVICKER, a citizen of the United States, residing at Milwaukee, in the county of Milwaukee and 5 State of Wisconsin, have invented a certain new and useful Improvement in Rail-Anchor Tie Plates, of which the following is a full, clear, concise, and exact description, reference being had to the accompanying drawings, forming a part of this specification.

This invention relates to rail anchor tie plates.

In some stretches of track it is a practical 15 impossibility to permanently and absolutely fix the rails against vertical vibration resulting from the peculiar wavelike or weaving action induced therein by the intensive localized loads momentarily imposed by the 20 passing traffic. Attempts to prevent this vertical vibration usually result in severe wear upon the rail securing means with ultimate failure of the parts affected.

One object of the present invention is the 25 provision of a rail anchor tie plate which will permit limited vertical vibration of the rail and at the same time effectively secure the same against side thrust and longitudinal creeping.

Another object is the provision of an effective tie plate of simple form which may be manufactured at slight cost.

Other objects and advantages will appear 35 from the following description of the embodiments of the present invention.

In the drawings:

Figure 1 is a plan view of a tie plate constructed in accordance with the present invention and showing the same applied to a 40 rail of standard form.

Figure 2 is a sectional view taken on the line 2—2 of Figure 1.

Figure 3 is a perspective view of a rail clamp employed.

Figure 4 is a plan view of a tie plate somewhat different in form embodying features of the present invention.

Figure 5 is a sectional view taken on the line 5—5 of Figure 4.

Figure 6 is a sectional view taken on the line 6—6 of Figure 4.

The tie plate shown in Figures 1 and 2 is formed from a substantially rectangular heavy steel plate 10, approximately one half 55 inch thick, although the thickness may vary

from about three eighths to three quarters of an inch, depending upon the service for which it is intended. Two integral hooks 11 are provided adjacent diagonal corners 60 of the plate. Each hook is formed by striking up a corner of the plate and shearing the same from the body of the plate, substantially along the line 12, so as to leave the struck up portion or tang, thus formed, integrally connected at one end to the plate. The struck up portions are then bent over on 65 themselves to provide permanent hooks of appropriate form adapted to overhang the opposite side flanges 13 of the base of the rail 14. Two slots 14 are punched through 70 the plate. Each slot 14 is positioned so as to extend beneath the rail substantially opposite one of the hooks 11. A substantially U-shaped rail clamp 15 is associated with 75 each slot and adapted to embrace the edge of one of the flanges 13. Each clamp comprises an upper jaw 16 overlying a rail flange and a lower jaw 17, seated in a slot 14, and underlying the flange. Each clamp is held in place by a spike 18 of usual form 80 driven through the outer end of the slot 14 into the tie 19. Each clamp is securely bound to the rail flange by a wedge 20 driven into position between the jaw 16 and the upper face of the rail flange. The jaw 85 16 is preferably notched as at 21 or otherwise fashioned to provide an appropriate retaining seat for the wedge.

In applying the tie plate it is first turned to a diagonal position beneath the rail, so 90 as to permit the hooks to clear the rail flanges, then lifted upwardly against the bottom of the rail, and then turned into the position shown, so as to cause the hooks 11 to overhang the rail flanges. The plate is 95 then adjusted along the rail into the desired position on the tie. The clamps 15 are then inserted into the slots 14 with their lower jaws 17 underlying the rail flanges, 100 and the spikes 18 driven into position behind the clamps. The spikes thus not only retain the clamps in rail embracing position, but also serve to secure the tie plate to the tie. The wedges 20 are then driven between the upper jaws 16 of the clamps and the top of the rail flanges so as to effect a firm grip between the clamps and the rail.

It will be noted from an inspection of Figure 2 that there is a slight clearance 22 between each hook 11 and the top of the as- 110

- sociated rail flange. It will also be noted that although the clamps 15 are securely bound to the rail, there is nothing to prevent vertical movement between the clamps 5 15 and the tie plate. A slight vertical play of the rail with respect to the tie plate is thus permitted, the extent of this play being determined by the clearance 22 beneath the upper jaws of the hooks 11.
- 10 However, the rail is securely held against lateral play by the engagement of the flanges thereof against the bodies of the hooks 11, and longitudinal creeping is prevented by the engagement of the lower jaws 17 of 15 the clamps within the slots 14. Any tendency to creep causes the clamps to rock slightly so as to increase their grip upon the rail.

The wedges 20 are driven up from time 20 to time to compensate for wear and are preferably retained in position by bending up the ends in the manner indicated.

Additional holes 23 are preferably provided through the tie plate to accommodate 25 additional spikes when occasion arises.

The tie plate shown in Figures 4, 5 and 6 is similar in many respects to that described in my Patent No. 1,460,819, issued July 3, 1923. This tie plate is formed from 30 a substantially rectangular heavy plate 10' of steel having portions 24 of its edges struck up to form thrust sustaining shoulders 25 adapted to bear against the edges of the rail base and to firmly hold the rail 35 against side play. The plate is punched to form openings, each having a narrow portion 26 extending beneath the rail and a wide portion 27. Portions 28 of the opposite edges of each opening are struck up out of 40 the plate, to form additional thrust sustaining shoulders and also to provide retaining means for rail clamps 29. Each rail clamp comprises upper and lower jaws 30 and 31, for embracing an edge of the rail base, 45 and a thickened base portion providing lateral lugs 32, adapted to engage beneath the struck up portions 28 of the tie plate. Each clamp is retained in position by means of a spike 33 driven into the opening 27 behind 50 the clamp and into the tie. A wedge 34 driven into position between the upper jaw 30 of each clamp and the rail flange insures a firm grip between the clamp and rail. The upper jaw 30 of each clamp is 55 preferably grooved, as at 35, to provide an appropriate seat for the wedge, the wedge being retained in position by bending up the end thereof, as indicated.

It will be noted from Figure 5 that a 60 slight clearance is provided at 36 between the lugs 32 of the clamp and the bent up portions 28. This clearance permits slight vertical vibration of the rail with respect to the tie plate and determines the extent 65 of such vibration. The engagement of the

lower jaw 31 of each clamp in the narrow opening 27 in the tie plate effectively prevents creeping of the rail.

Openings 37 punched through the tie plate permit the use of additional spikes 70 when occasion arises to more firmly secure the tie plate to the tie.

Various changes may be made in either of the embodiments of the invention hereinabove described, without departing from or 75 sacrificing any of the advantages of the invention as defined in the appended claims.

I claim:

1. In a rail anchor tie plate the combination of a tie plate having an opening therein, a rail clamp engaged in said opening and embracing an edge of a rail, and a wedge between said clamp and rail to bind said clamp to the rail. 80

2. In a rail anchor tie plate the combination of a tie plate having an opening therein, a rail clamp embracing an edge of a rail and engaged in said opening, means for retaining said clamp in rail embracing position, and a wedge between said clamp 90 and rail to bind said clamp to the rail. 85

3. In a rail anchor tie plate the combination of a tie plate having an opening therein, a rail clamp embracing an edge of a rail and engaged in said opening, a spike 95 driven through said opening behind said clamp for retaining said clamp in rail embracing position, and a wedge between said clamp and rail to bind said clamp to the rail. 100

4. In a rail anchor tie plate the combination of a tie plate having an opening therein, a rail clamp embracing an edge of a rail and engaged in said opening, a wedge firmly binding said rail clamp to the rail, 105 said rail clamp and rail being vertically movable with respect to said tie plate, and means for limiting such vertical movement.

5. In a rail anchor tie plate the combination of a tie plate having an opening 110 therein, a rail clamp embracing an edge of a rail and engaged in said opening, a spike driven through said opening behind said clamp to retain said clamp in rail embracing position, a wedge firmly binding said clamp to said rail, said clamp and rail being vertically movable with respect to said tie plate, and means for limiting such vertical movement. 115

6. In a rail anchor tie plate the combination of a tie plate, a rail clamp embracing an edge of a rail and engaged with said tie plate, a wedge firmly binding said clamp to said rail to prevent creeping, means for securing said tie plate to a tie, said clamp 125 and rail being vertically movable with respect to said tie plate, and means for limiting such vertical movement.

7. In a rail anchor tie plate the combination of a tie plate having means for sus- 130

taining side thrusts of a rail, a rail clamp embracing an edge of the rail, a wedge firmly binding said clamp to the rail to prevent creeping of the rail, said clamp and rail being vertically movable with respect to said tie plate, and means for limiting such vertical movement.

8. In a rail anchor tie plate the combination of a tie plate having a hook overlying a base flange of a rail and permitting limited vertical vibration thereof, a clamp embracing an edge of the rail and engaged with said tie plate for vertical movement with respect thereto, and a wedge for firmly binding said clamp to the rail to prevent creeping.

9. In a rail anchor tie plate the combination of a tie plate having a permanent hook portion bent up from the body of said plate, said hook portion being formed to overlie a base flange of a rail, a clamp for embracing an edge of the rail, a wedge for firmly binding said clamp to the rail to prevent creeping of the rail, and means for securing said tie plate to a tie and to retain said clamp in rail embracing position.

10. In a rail anchor tie plate the combination of a substantially rectangular plate having a portion bent up out of the body of the plate to form a hook portion for retaining a rail on said plate, a rail clamp embracing an edge of a rail flange and engaged with said plate, and a wedge for binding said clamp to the rail to prevent creeping of the rail.

11. In a rail anchor tie plate the combination of a substantially rectangular plate having diagonal corners thereof bent up out

of the body of the plate to form hook portions for engaging over opposite base flanges of a rail, means for securing said plate to a tie, and means associated with the base of the rail and tie plate to prevent creeping of the rail.

12. In a rail anchor tie plate the combination of a substantially rectangular plate having diagonal corners thereof bent up out of the body of the plate to form hook portions for engaging over opposite base flanges of a rail, a clamp embracing each of said flanges and engaged with said plate, and a wedge associated with each clamp to bind the same to the rail to prevent creeping of the rail.

13. In a rail anchor tie plate the combination of a tie plate having a slot therein extending beneath a base flange of a rail and means for sustaining side thrusts of the rail, a U-shaped clamp engaged in said slot and embracing an edge of said flange, and a wedge inserted between said clamp and the top of said flange to bind said clamp to the rail.

14. In a rail anchor tie plate the combination of a tie plate having a slot therein extending beneath a base flange of a rail and means for sustaining side thrusts of the rail, a U-shaped clamp engaged in said slot and embracing an edge of said flange, means for retaining said clamp in rail engaging position, and a wedge inserted between said clamp and the top of said base flange to bind said clamp to the rail.

In witness whereof, I hereunto subscribe my name this 7th day of March, 1925.

EMERY M. McVICER.
